OSCILLATING SEAT

Robert C. Swengel, York, Pa.

Application October 9, 1946, Serial No. 702,196

10 Claims. (Cl. 155—56)

1

This invention relates to an exercising toy of the hobby-horse type and more particularly to a structure of this character in which oscillatory movement of a body support from a normal central position is accomplished by physical effort of the occupant and is opposed by springs to an extent proportional to the displacement of the support from said position, and is an improvement of the structure shown in my now abandoned application Serial No. 705,995 filed October 26, 1946, for Hobby Horses.

Important objects of the invention are, the provision of a construction of this character such that the spring resistance can be very readily regulated, in which the springs serve to maintain assembly of the body support with its supporting members and which may be very readily assembled and disassembled.

These and other objects I attain by the construction shown in the accompanying drawings in which:

Figure 1 is a perspective view partially broken away of a toy constructed in accordance with my invention, the dotted lines indicating one deflected position of the body support;

Figure 2 is a section on line 2—2 of Figure 3;

Figure 3 is a section on line 3—3 of Figure 2, and

Figure 4 is a section on line 4—4 of Figure 2.

Referring now more particularly to the drawings, the numeral 10 designates a base, 11 a body support and 12 substantially parallel members disposed transversely of the base 10, pivoted at their lower ends thereto at 13 and extending generally vertically therefrom. The upper ends of members 12 support body support 11 in a manner hereinafter described.

Base 10 may be of any desired conformation being at present shown as comprising parallel side members 14 mounting pivots 13 and connected by upwardly bowed transverse members 15 which serve to positively limit deflection of the body support 11 in either direction through their engagement with members 12.

The members 12 may be of any suitable construction insuring their rigidity against deflection in a direction transverse to the base, providing for pivotal mounting at 13, so that they may swing in a direction longitudinal to the base and affording at their upper ends a transversely disposed bearing engaging element 16. As at present disclosed, they comprise inverted U-shaped members the lower ends of the arms of which are engaged by pivots 13 and the bight portions of which form the bearing engaging elements 16.

2

Bearing engaging elements have secured thereto ears 17 horizontally disposed, and spaced to support between the free ends thereof a bar 18, parallelling the element 16, the purpose of which will presently appear. As shown these ears 17 are disposed on opposed sides of the elements 16.

The body support comprises a seat 19, attached to the under surface of which is a bracket 20, the ends of which are formed as oppositely and outwardly facing hooks 21. Fixed in these hooks are outwardly open bearing sockets 22, receiving in the order named a shock-absorbing pad 23, preferably of rubber, and an outwardly open U-shaped bearing 24. Socket 22 pad 23 and bearing 24 may be secured to one another in any suitable manner.

Bearings 24 receive the transversely disposed bearing engaging elements 16 and assemblage is completed by connecting bars 18 by one or more springs 25 thereto by engaging the hooked ends 26 of the spring or springs over the bars. Obviously, these springs will be least tensioned in the normal central position of body support 11 and will be increasingly tensioned as the body support moves from this normal position in either direction. The resistance to displacement can be readily regulated by varying the number of springs 25 which are employed thus enabling ready adaptation of the toy for use by children of different weights. Attention is directed to the fact that springs 25 in addition to their function of opposing movement of the body support serve to maintain assembly of the elements 16 with bearings 24. In this connection it will be noted (Figure 2) that bars 18 are, when the unit is in its normal vertical position, spaced from the backs of their associated bearing receiving hooks 21 a distance such that even though a bar 18 be engaged with its associated hook and the seat moved vertically the member 12 cannot be disengaged from its bearing. A comparison of the dotted and solid lines in Figure 2 will render it obvious that a similar relative engagement between hooks 21 and bars 18 continues, not only while the parts

40 are moving between the illustrated positions but for a considerable additional reduction in the angle between the seat and members 12. Since the tension of springs 25 will increase progressively from the solid line position of Figure 2 to the ultimate angular position in which the member 12 is separable from its bearing, it will be obvious that the only method of separating these elements is to remove the springs 25 while the 50 elements are in the solid line position of Figure 2.

and then move the structure to the position of disengagement.

It will also be noted from Fig. 3 particularly that the seat 19 overlies and substantially extends laterally beyond said ears 17, bars 18, and springs 25, and all of the elements are in close spaced relationship to the undersurface of seat 19, whereby the legs of a child or other person seated on said seat are prevented from accidentally being pinched or injured by said elements when the hobby horse is in use.

To provide for operation, one of the members 12 is provided with oppositely projecting rigid stirrups 27 for reception of the feet of the rider and the body support 11 is provided, at the corresponding end thereof, with a head 28 having oppositely extending hand-grips 29. As shown, the body support is preferably provided with a skirt 30 concealing the spring and bearing element.

Since the structure illustrated is obviously capable of considerable modification without departing from the spirit of my invention, I do not wish to be understood as limiting myself to the present disclosure except as hereinafter claimed.

What I claim is:

1. In a toy of the class described, a base, a pair of inverted U-shaped members pivoted at the lower ends thereof to said base and extending upwardly therefrom in substantial parallelism, a body support having horizontally oppositely opening segmental bearings receiving the bight portions of said U-shaped members, means on said bight portions projecting laterally toward each other, and springs interconnected to said means on said bight portions of said U-shaped members and serving to hold said bight portions in operative position in said bearings, said springs and said means on said bight portions being so arranged that oscillation of said U-shaped members from a normal vertical position to an inclined position at either side of such vertical position creates an increasing tension in the springs resisting such oscillation in a degree proportionate to the deflection.

2. In a toy of the class described, a base, a pair of inverted U-shaped members pivoted at the lower ends thereof to said base and extending upwardly therefrom in substantial parallelism, a body support having horizontally oppositely opening segmental bearings receiving the bight portions of said U-shaped members, a pair of spaced arms projecting from and fixed to each bight portion and extending toward the other thereof, a bar connecting the ends of said arms, and tension springs connecting said bars and holding said bight portions in position in said bearings.

3. In a toy of the class described, a base, a pair of inverted U-shaped members pivoted at the lower ends thereof to said base and extending upwardly therefrom in substantial parallelism, a body support having horizontally oppositely opening segmental bearings receiving the bight portions of said U-shaped members, a pair of spaced arms projecting from and fixed to each bight portion and extending toward the other thereof, a bar connecting the ends of said arms, and tension springs connecting said bars and holding said bight portions in position in said bearings and said arms being engaged with the ends of said bearings to thereby prevent transverse shifting of said body support.

4. In a toy of the class described, a base, a pair of inverted U-shaped members pivoted at the lower ends thereof to said base and extend-

ing upwardly therefrom in substantial parallelism, a body support having horizontally oppositely opening segmental bearings receiving the bight portions of said U-shaped members, a pair of spaced arms projecting from and fixed to each bight portion and extending toward the other thereof, a bar connecting the ends of said arms, and tension springs connecting said bars and holding said bight portions in position in said bearings, said bars being of a length to receive the ends of a plurality of springs whereby by adding or removing a spring or springs the effort required to produce a given angular deflection of the U-shaped members may be varied.

5. In a toy of the class described, a base, a pair of members pivoted upon parallel axes at the lower ends thereof to said base and extending upwardly therefrom in substantial parallelism, said members having horizontal portions at the upper ends thereof which extend transversely of the base, a body support having horizontally oppositely opening segmental bearings receiving said portions of said members, a pair of spaced arms projecting from and fixed to each of said portions and extending toward the other thereof, a bar connecting the ends of said arms, and tension springs connecting said bars and holding said portions in position in said bearings.

6. In a toy of the class described, a base, a pair of members pivoted upon parallel axes at the lower ends thereof to said base and extending upwardly therefrom in substantial parallelism, said members having horizontal portions at the upper ends thereof which extend transversely of the base, a body support having horizontally oppositely opening segmental bearings receiving said portions of said members, a pair of spaced arms projecting from and fixed to each of said portions and extending toward the other thereof, a bar connecting the ends of said arms, and tension springs connecting said bars and holding said portions in position in said bearings and said arms being engaged with the ends of said bearings to thereby prevent transverse shifting of said body support.

7. In a toy of the class described, a base, a pair of members pivoted upon parallel axes at the lower ends thereof to said base and extending upwardly therefrom in substantial parallelism, said members having horizontal portions at the upper ends thereof which extend transversely of the base, a body support having horizontally oppositely opening segmental bearings receiving said portions of said members, a pair of spaced arms projecting from and fixed to each of said portions and extending toward the other thereof, a bar connecting the ends of said arms, and tension springs connecting said bars and holding said portions in position in said bearings, said bars being of a length to receive the ends of a plurality of springs whereby by adding or removing a spring or springs the effort required to produce a given angular deflection of the members may be varied.

8. In a toy of the class described, a base, a pair of members pivoted upon parallel axes at the lower ends thereof to said base and extending upwardly therefrom in substantial parallelism, said members having horizontal portions at the upper ends thereof which extend transversely of the base, a horizontal body support having horizontally oppositely opening segmental bearings receiving said portions of said members, arms projecting from and fixed to each of said portions and extending toward the other thereof,

tension springs operatively connecting said arms and holding said portions in position in said bearings, and means preventing disengagement of said portions from said bearings until the body support and said members are in acute angular relation to one another.

9. A device as claimed in claim 8 wherein said horizontal portions comprise bars secured to said arms, said bars being positioned relative to said bearings so as to be engageable therewith when attempting to disengage said members from said bearings except when said members and body support are acutely angularly related.

10. A device as claimed in claim 8 wherein said horizontal portions comprise bars secured to said arms, said bars being positioned relative to said bearings so as to be engageable therewith when

5

10

15

attempting to disengage said members from said bearings except when said members and body support are acutely angularly related, said bars also being directly engaged by said springs.

ROBERT C. SWENGEL.
